WILLIAM C. DAVIS, OF PRESTON, WASHINGTON

SHINGLE AND METHOD OF MAKING SAME

Application filed April 15, 1929. Serial No. 355,292.

My invention relates to improvements in wood shingles and particularly to a method of making the same.

It is an object of the invention to provide a shingle having a natural rustic appearance which will impart an artistic effect to the roof or other surface.

A further object of the invention is to provide a shingle having the naturally split grain of the wood on the upper surface, adjacent the butt end of the shingle and the surface adjacent the tip of the shingle smooth.

Another object of the invention is to provide a shingle which is simple and practical in construction, efficient in use and inexpensive to manufacture.

Other objects and advantages of the invention will be apparent during the course of the following description.

20 In the accompanying drawing, forming a part of this specification and in which like numerals are employed to designate like parts throughout the same,

Fig. 1, is a perspective view of a block of wood from which my improved shingle is made,

Fig. 2, is an end view of the block showing a slot cut in the upper end, preparatory to splitting the same,

30 Fig. 3, is an end view showing the block split, and,

Fig. 4, is a front elevation of my improved shingle.

In the drawing, wherein for the purpose of illustration, I have shown a preferred embodiment of my invention, the numeral 5 denotes generally my improved shingle which is tapered, substantially uniformly from butt to tip and has a smooth plane bottom face 6, which face contacts with the roof or other surface to be covered. The upper surface of the shingle has a smooth plane face 7, adjacent the tip of the shingle and the portion of the upper surface adjacent the butt end has the naturally split grain of the wood providing a rustic appearing face 8 which face is exposed to the weather. The smooth face 7 of the shingles are overlapped by the butt ends of the next row of shingles, establishing a weather tight connection between

the rows of shingles. In making the shingles a shoulder 9 is formed between the smooth face 7 and the split grain face 8, which may serve as an abutment for the butt ends of the next row of shingles or may be eliminated by cutting the shoulder down. When the shoulder is provided it must be formed within one-third of the length of the shingle from the butt for spaced shingles and within one-half the length of the shingle from the butt for abutting shingles.

The shingles are made by taking a tapered block 10 having smooth plane faces 11 and 12, cutting a vertical slot 13 in the upper end of the block by sawing the tip along its longitudinal center line, the slot extending down to a point less than one-half the length of the block and then splitting the block longitudinally for the rest of its length, as more clearly shown in Fig. 3. Thus, it is seen that two shingles are formed having a smooth plane bottom face 6, smooth plane upper face 7 and split grain face 8. By this method of construction I provide a shingle having all the advantages of the common machine made shingle and yet the exposed face of shingle will have a rustic appearance imparting an artistic effect to the roof or other surface. In actual practice it will be found that the butt end of the shingle will vary in thickness due to the splitting of the block which adds to the rustic appearance of the shingle and if desired the butt end may be provided with an irregular cut edge to add to the rustic appearance.

It is to be understood that the form of my invention herewith shown and described is to be taken as a preferred example of the same and that certain changes in the shape, size and arrangement of the parts may be made without departing from the spirit of the invention or the scope of the subjoined claims.

Having thus described my invention, I claim:

1. The method of forming shingles from a block of wood, which consists in initially slotting the block and then splitting the shingle off the block.
2. The method of forming shingles from

a block of wood which consists in cutting the block to provide an inclined smooth surface, slotting the block longitudinally of the grain of the wood and then splitting the shingle off the block.

5 3. The method of forming shingles from a tapered block of wood which consists in initially slotting the tip of the block along its longitudinal center line and then splitting
10 the block.

In testimony whereof I affix my signature.

WILLIAM C. DAVIS.
